CUSHIONED PACKING INSERT

Larry J. Budd, Elmhurst, Ill., assignor to Pallet Devices, Inc., Des Plaines, Ill., a corporation of Illinois
Filed Oct. 3, 1962, Ser. No. 228,174
11 Claims. (Cl. 229—14)

The present invention relates generally to a cushioning pad for insertion into a carton for end engagement with an article to be disposed in the carton. This invention further relates to a method for manufacturing the cushioning pad.

In an exemplary application of this invention, a television receiver including a cabinet and receiver apparatus therewithin, underlying the cabinet to support the cabinet bottom wall is spaced in relation to the container bottom as shown in the U.S. Patent No. 2,895,661. The cushioning pad is adapted to be disposed over the cabinet top and carries means depending therefrom for engaging upper portions of the front wall, rear walls and side walls of the cabinet to support the same in spaced relation to the vertical walls of the container and also to protect the edges of the cabinet at the inner sections of the top wall with the front wall, rear wall and side wall.

The cushioning pads herein disclosed are improvements upon the cushioning pad disclosed in my aforesaid patent whereby the instant cushioning pads can be more readily manufactured at a reduced cost. The instant cushioning pads are sturdier and stronger than the cushioning pad disclosed in my aforesaid patent according to important features of this invention. To attain this end, a paperboard plate is secured within a central pocket of the pad and which pad is peripherally defined by rectangularly arranged, reinforced cushioning tubes. The outer edges of the paperboard plate are engaged in edgewise reinforcing relation against the rectangularly arranged tubes for maintaining the tubes in an upright position relative to the central portion of the cushioning pad. In order to further reinforce the cushioning pad, side tubes are provided with inside side walls having notched areas which are engaged against inside and bottom side walls of the rear tube and with bottom walls of the side tubes being secured in lapped engagement with a bottom wall of the rear tube.

There are two types of cushioning pads disclosed herein, one of which is particularly adapted for being mounted on a television apparatus and the other of which is suited for being mounted on a stereo cabinet. It will be appreciated that the television tube extends rearwardly of the television cabinet and this tube must be protected by the cushioning pad. Since a stereo cabinet does not have a television tube, the front and rear tubes on the pad may be manufactured identical to one another.

It is an important object of this invention to provide a new and improved cushioning pad which may be more easily manufactured at a reduced cost.

Still another object of this invention is to provide a new and improved cushioning pad which is sturdier than similar pads previously used.

Yet another object of this invention is to provide a new and improved method for manufacturing the cushioning pads described above.

A still further object of this invention is to provide a new and improved cushioning pad having a central plate with its peripheral edges butt engaged with the inside walls of the tubes disposed on one side of the pad and further with the plate edges serving to hold the inside walls in engagement with the reinforcing means disposed within the tubes.

Still another feature of this invention relates to a new and improved method of securing a paperboard plate with

2

a cushioning pad to hold rectangularly arranged reinforcing tubes in upright position on the pad. Other objects and features of this invention will more fully become apparent in view of the following detailed description taken in conjunction with the accompanying drawings illustrating several embodiments and in which:

FIGURE 1 is a view illustrating a sheet or blank from which the cushioning pad is formed and with a paperboard plate being superimposed thereon for illustrating its relative position with respect to the sheet;

FIGURE 2 is a bottom view of a cushioning pad, in accordance with the principles of this invention;

FIGURE 3 is an end view of the cushioning pad shown in FIGURE 2;

FIGURE 4 is a fragmentary enlarged vertical section taken substantially on the line IV—IV looking in the direction indicated by the arrows as shown in FIGURE 2;

FIGURE 5 is a fragmentary enlarged vertical section taken substantially on the line V—V looking in the direction as shown by the arrows in FIGURE 2;

FIGURE 6 is a fragmentary enlarged vertical section taken substantially on the line VI—VI looking in the direction as shown by the arrows in FIGURE 2;

FIGURE 7 is an enlarged fragmentary view showing the manner in which one of the tubes is secured to a reinforcing insert;

FIGURE 8 is a fragmentary side view, partially in section, illustrating a carton having a cushioning pad mounted on a television receiver;

FIGURE 9 is a bottom view of a modified type of cushioning pad; and

FIGURE 10 is a fragmentary end view of the pad as viewed on the line X—X looking in the direction indicated by the arrows as shown in FIGURE 9.

In FIGURE 8 the reference numeral 7 indicates a paperboard carton 7 having a television receiver 8 mounted therein and with a cushioning pad or cushioned packing insert 9 mounted on top of the receiver 8 for protecting the receiver within the carton 7 during shipment. The cushioning pad 9 in FIGURE 8 and the cushioning pad 9' in FIGURE 9 and the methods of making the same embody the inventive concepts presented herein.

In general, each of the cushioning pads may be formed from relatively rigid form-sustaining sheet material and preferably for an inexpensive expendable material such as paperboard, fiberboard or the like. The pads are formed by making bends at score lines which may be scored by marking the blank or preferably by actual indentation of the blank, especially when the blank is of paperboard or a like material, but it will be appreciated that marking or indentation is not necessarily required and the terms "scoring" and "score line" are therefore used in a figurative sense to indicate the position of the bends.

The cushioning pad 9 is formed by cutting, scoring and folding a cushioning pad blank or sheet 10 in the manner hereafter described. The blank 10 includes a central pad portion or area 11 having four blank or sheet margins 12, 13, 14 and 15. The sheet margin 12 is scored along score lines 16, 17 and 18 to provide flaps or sections 19, 20 and 21. The flap 17 is provided with a notch area 22 having a configuration approximating the peripheral dimension of the rear tubular disclosure hereafter described. The sections 19, 20 and 21 are folded at the score lines

16, 17 and 18 about a reinforcing insert 23 to form a reinforced side tube or tubular enclosure 24. The packing may be comprised of any suitable material such as layers of corrugated paper with the corrugations extending transversely of the tube 24. Other suitable types of reinforcing inserts may be used, if desired.

The margin 13 is scored with score lines being indicated

at 25, 26 and 27 to form tube sections or flaps 28, 29 and 30. A reinforcing insert 31 which is substantially identical to the insert 23 is adapted to be disposed interiorly within reinforced rear tube or tubular enclosure 32 upon folding the tube sections 28, 29 and 30 at the score lines 25, 26 and 27 about the insert 31.

The margin 14 is scored as indicated by score lines 34, 35 and 36 to form tube sections 37, 38 and 39. The tube section 39 is provided with a notch area 40 of the same type as the notch area 22 for snug engagement with tube flaps or sections 29 and 30 on the tube 24. The margin 14 is adapted to be folded along the score lines to turn the tube sections 37, 38 and 39 about a reinforcing insert 41 to form a reinforced side tube or tubular enclosure 42.

The fourth margin 15 is provided with a T-shaped notch area 44 providing a pair of pad blanks with the first pad blank being scored as indicated by score lines 45, 46 and 47 to form pad sections 48, 49 and 50. These pad sections are folded about a reinforcing insert or filler 51 to form a reinforced front tube 52. The other pad blank is scored along score lines 54, 55 and 56 to form pad sections 57, 58 and 59. These pad sections are folded about a reinforcing insert 60 to form a reinforced front tube 61.

As the reinforced tubes 24, 32, 42, 52 and 61 are formed, the reinforcing inserts are preferably glued by a suitable glue such as a vegetable base glue with the surrounding flaps as well as the central pad portion or area 11 for holding the tubes in a plane generally normal to the plane of the central pad portion 11. In order to further rigidify the tubes 24, 32 and 42, the tube flaps or sections 20 and 38 on the side tubes 24 and 42 are glued to the flap or section 29 on the rear tube 32. Still further, in order to rigidify the juncture between the tube 24 and 52 and the juncture between the tubes 52 and 61, the flaps or sections 21 and 50 are glued together and the flaps or sections 39 and 59 are glued together as shown in FIGURE 3.

In view of the foregoing it will be appreciated how the cushioning pad 9 can be formed from a reduced amount of material and yet be of a very rigid construction. In order to further rigidify the pad 9, and according to still further important features of this invention, a paperboard reinforcing plate 63 is pressed against the central pad portion or area 11 and preferably secured thereto by means of glue or the like in such manner that its marginal edges 64, 65, 66 and 67 are engaged with the inner side walls defined by the flaps or sections 21, 30, and 39 as well as against the tubes 52 and 61. The plate 63 is cut to a dimension which corresponds precisely to the dimension of the top of the television receiver 8. By securing the plate 63 with the pad 9 in the manner described, the tubes 24, 32, 42, 52 and 61 are all reinforced as a result of the engagement of the marginal edges of the plate 63 therewith. The marginal edge 67 engages with end edges of the tubes 52 and 61 rather than with the side walls of the tubes and it will be appreciated that such engagement serves to rigidify the pad 9 to better enable the pad to resist forces tending to displace the tubes with respect to the central pad portion or area 11.

Shown in FIGURES 9 and 10 is the modified cushioning pad 9'. This pad 9' is identical to the pad 9 except that the tubes 52 and 61 found on the pad 9 are replaced by a reinforced side tube or tubular enclosure 32" which is identical to reinforced side tube or tubular enclosure 32'. The tube 32' is identical to the tube 32 previously described in connection with the pad 9. In order to further rigidify the pad 9, opposite ends of side tubes 20' and 42' are notched as indicated at 22'-22' and 40'-40' to enable the tube side walls to be fitted about rear and front tubes 32' and 32" for reinforced engagement therewith. It will thus be appreciated that the opposite ends of the tubes 20' and 42' are engaged in fitted relation in glued assembly with rear and front tubes 32' and 32" in contrast to the pad 9 where the tubes 20 and 42 were only notched at one end for engagement with the rear tube 32.

The pad 9' is adapted for use with a conventional cabinet whereas the pad 9 is adapted for assembly with a television receiver cabinet 9'. In this regard, the tubes 52 and 58 are adapted to extend rearwardly of the television receiver cabinet 8 to protect the television tube which extends rearwardly behind the television receiver cabinet on most conventional types of television receiver sets.

It will be understood that modifications and variations may be effected without departing from the scope of the novel concepts of the present invention.

I claim as my invention:

1. A cushioning pad comprising,

a parallel sided sheet of paperboard having at least three of its margins scored along three spaced lines providing three flaps along each of said margins with an opposite pair of the margins each having an outer most flap having a cut-away notch area at its corner, the three scored margins being folded at the scorelines disposing the outer most flaps in normal relation to a central area of the sheet forming a tubular enclosure along at least three sides of the central area including parallel enclosures and a transverse enclosure packing in said tubular enclosures, and a relatively flat paperboard plate attached with a central area of the sheet and having its outer edges engaged against inside walls of said outer most flaps of said tubular enclosures holding said flaps snugly against said packing,

one of said flaps on said parallel enclosures being lapped on top of and secured with a confronting one of the flaps on the transverse enclosure extending between the parallel enclosures securing said enclosures in upright folded relation about the central area of the sheet disposed there between and with each of said cut-away notch areas being peripherally fitted about a pair of the folded flaps on the transverse enclosure.

2. A cushioning pad comprising,

a parallel sided sheet of paperboard having its four margins scored along three spaced lines providing three flaps along each of said margins with an opposite pair of the margins each having an outer most flap having a cut-away notch area at its corner at each end, the scored margins being folded at the scorelines disposing the outer most flaps in normal relation providing a central area of the sheet with a tubular enclosure about four sides of the central area including parallel enclosures and a transverse enclosure, packing in said tubular enclosures, and a relatively flat paperboard plate attached with said central area of the sheet and having its outer plate edges engaged against inside walls of said outer most flaps of said tubular enclosures holding said flaps snugly against said packing,

one of said flaps on said parallel enclosures being lapped on top of and secured with a confronting one of the flaps on the transverse enclosure extending between the parallel enclosures securing said enclosures in upright folded relation about the central area of the sheet disposed there between and with each of said cut-away notch areas being peripherally fitted about a pair of the folded flaps on the transverse enclosure.

3. In a method of forming a cushioning pad, the steps

of scoring a paperboard sheet at its four margins and folding the margins at the scoring forming cushioning tubes,

securing the tubes in upright position about an outer margin of one side of a central portion of said sheet with the tubes being cooperable with the central portion in defining a central pocket, and pressing a paperboard plate into the central pocket engaging its four plate margins in edgewise rigidifying rela-

tion with respect to said marginal tubes and securing said paperboard plate in bottomed relation against said central portion of said sheet.

4. In a method of forming a cushioning pad, the steps of scoring a paperboard sheet at its four margins and folding the margins at the scoring forming cushioning tubes with tab portions on opposite margins being lapped on top of one of said tubes disposed transversely thereof,

securing the tubes in upright position about an outer margin of one side of a central portion of said sheet while securing the tab portions with the tube disposed transversely thereof for holding the tubes erect in normal relation to the central portion and with the tubes being cooperable with the central portion in defining a central pocket, and

pressing a paperboard plate into the central pocket engaging its four plate margins in edgewise rigidifying relation with respect to said marginal tubes and securing said paperboard plate in bottomed relation against said central portion of said sheet.

5. In a method of forming a cushioning pad, the steps of scoring a paperboard sheet at its four margins and folding the margins at the scoring forming cushioning tubes with tab portions on opposite ends of opposite tubes being lapped on top of the associated tubes disposed transversely thereof,

securing the tubes in upright position about an outer margin of one side of a central portion of said sheet while securing the tab portions with the tubes disposed transversely thereof for holding the tubes erect in normal relation to the central portion and with the tubes being cooperable with the central portion in defining a central pocket, and

pressing a paperboard plate into the central pocket engaging its four plate margins in edgewise rigidifying relation with respect to said marginal tubes and securing said paperboard plate in bottomed relation against said one side of said central portion of said sheet.

6. In a method of forming a cushioning pad, the steps of scoring a paperboard sheet at its four margins and folding tube side walls at the scoring forming cushioning tubes with reinforcing inserts being disposed inside of said tubes securing the tubes in upright position about an outer margin of one side of a central portion of said sheet with the tubes being cooperable with the central portion in defining a central pocket, and

pressing a paperboard plate into the central pocket engaging its four plate margins in edgewise rigidifying relation with respect to the tube side walls of said marginal tubes engaging the adjacent side walls in snug rigidified engagement against the reinforcing inserts and securing said paperboard plate in bottomed relation against said central portion of said sheet.

7. In a cushioning pad comprised of:

a relatively flat paperboard sheet scored at its four margins providing cushioning tube side walls forming cushioning tubes on one side of a central portion of said sheet with an opposite side of said central portion comprising a flat unobstructed surface,

the tubes being secured in upright position about an outer margin of one side of a central portion of said sheet with the tubes being cooperable with the central portion in defining a central pocket, and

a relatively flat paperboard plate secured inside said central pocket in bottomed engagement against said one side of said central portion and with plate margins of said plate engaged in edgewise rigidifying relation with opposing ones of said tube side walls of said tubes.

8. In a cushioning pad comprised of:

a relatively flat paperboard sheet scored and bent at

its four margins providing cushioning tube side walls forming cushioning tubes on one side of a central portion of said sheet with an opposite side of said central portion comprising a flat unobstructed surface,

the tubes being secured in upright position about an outer margin of one side of a central portion of said sheet with the tubes being cooperable with the central portion in defining a central pocket, reinforcing inserts secured inside said cushioning tubes, and

a relatively flat paperboard plate secured inside said central pocket in bottomed engagement against said central portion and with marginal edges of said plate engaging said tube side walls in edgewise rigidifying relation with said paperboard plate pressing said side walls of said cushioning tubes in snug engagement against said inserts.

9. In a cushioning pad comprised of:

a relatively flat paperboard sheet scored at its four margins which margins are bent forming cushioning tubes on one side of a central portion of said sheet including front, side and rear tubes,

the tubes being secured in upright position about an outer margin of one side of a central portion of said sheet with the tubes being cooperable with the central portion in defining a central pocket,

said side tubes having inside side walls each provided with a notched area which notched areas are engaged against inside and bottom side walls of said rear tube and with said side tubes having ends of bottom side walls attached with said bottom side wall of said rear tube holding the side and rear tubes in an upright position relative to said central portion, reinforcing inserts secured inside said cushioning tubes, and

a relatively flat paperboard plate secured inside said central pocket in bottomed engagement against said central portion and with marginal edges of said plate engaging said tubes in edgewise rigidifying relation with said paperboard plate pressing said inside side walls of said cushioning tubes in snug engagement against said inserts.

10. In a cushioning pad comprised of:

a relatively flat paperboard sheet scored at its four margins which margins are bent forming cushioning tubes on one side of a central portion of said sheet including a pair of front tubes, a pair of side tubes and a rear tube,

the tubes being secured in upright position about an outer margin of one side of a central portion of said sheet with the tubes being cooperable with the central portion in defining a central pocket,

said front tubes each having three side walls and each including an outermost side wall secured in parallel face-to-face engagement with an inside side wall of one of said side tubes,

reinforcing inserts secured inside said cushioning tubes, and

a relatively flat paperboard plate secured inside said central pocket in bottomed engagement against said central portion and with marginal edges of said plate engaging said tubes in edgewise rigidifying relation with said paperboard plate pressing inside side walls of said side and rear cushioning tubes in snug engagement against said inserts and being engaged against end edges of said side walls on each of said front tubes.

11. In a cushioning pad comprised of:

a relatively flat paperboard sheet having box-shaped cushioning tubes at its margins on one side of the sheet, means securing the tubes in an upright position about an outer margin of one side of a central portion of the sheet, packing disposed internally of the tubes, and

a relatively flat paperboard plate secured against said one side of the sheet having outer margins engaged in right angular relation against tube flaps and co-operable with said means for holding said tube flaps against said filler and for holding said tubes in normal relation with respect to the central portion of the sheet.
